UNITED STATES PATENT OFFICE.

JOSEPH CONRAD PRICE, OF BALTIMORE, MARYLAND.

PIANO-ACTION.

SPECIFICATION forming part of Letters Patent No. 395,078, dated December 25, 1888.

Application filed September 17, 1888. Serial No. 285,650. (No model.)

To all whom it may concern:

Be it known that I, JOSEPH CONRAD PRICE, of Baltimore city, in the State of Maryland, have invented a new and useful Improvement 5 in Piano-Actions, of which the following is a specification.

My invention is an improvement in pianos, and seeks to provide a simple construction by which to avoid the looseness of action of the 10 key-levers consequent upon the lost motion between the hammer butt and jack when the hammers are raised toward the strings when the soft pedal is operated, and preserve the desired elasticity of touch under all circumstances. 15

The invention consists in the novel constructions and combinations of parts, as will be hereinafter described and claimed.

In the drawings, Figure 1 is a cross-section 20 of a portion of an upright piano provided with my improvements, parts being broken away and others shown in section. Fig. 2 is an elevation of part of my improvement. Figs. 3, 4, and 5 are detail views illustrating the 25 key-lifter.

By my invention I seek to provide convenient, simple constructions for lifting the rear ends of the keys when the soft pedal is operated to correspond with the movement of the 30 hammer-rest, effected by such movement of the soft pedal, so as to preserve the elasticity of the keys and cause all parts to work in harmony with each other.

The keys A are suitably supported, and 35 may be suitably constructed and connected at their rear ends to operate the hammers.

The key-frame B or the key-bottom E, below the keys, supports the key-lifter C, which lifter forms a rest for the rear end of the 40 keys and serves as a means of elevating the rear end of the keys, as desired. This lifter extends the length of the key-board under all the keys, and is hinged at its front or inner edge at c to the key-frame B or key-bottom 45 E, so it may be tilted on such hinge and be so elevated to lift the keys, the lifter being properly cushioned on its upper side to form a proper seat for the keys.

It will be noticed that the lifter is hinged 50 on or at the upper side of the frame B or key-

bottom E, and has a portion which extends down to the lower side of the key bottom or frame E, at the rear edge of the latter.

In the construction shown in Figs. 1 and 3 the main or body portion of the lifter is arranged above the key-bottom E, and a wing or flange-like portion, C', depends from the rear side of the said body portion along the rear edge of the said bottom E to the lower side thereof. 55

In the construction shown in Figs. 4 and 5 the body portion of the lifter is arranged along the rear edge of the key-frame. 60

The construction shown in Figs. 1 and 3 may be preferred, as thereby the hinges of 65 the lifter are relieved of the weight of the lifter when the latter is at rest, such weight being borne by the framing, as shown.

To operate the lifter, I provide the soft-pedal rocker D, at one end, with a projection 70 or portion, d, arranged to engage the lifter and elevate the same as the soft pedal F is depressed, such soft pedal being properly connected with the rocker D to operate same, as will be understood from Fig. 1. 75

The projection d preferably has a screw-threaded stem threaded into the rocker, so the height of said part d may be adjusted. At its opposite end the rocker is connected with a slide-rod, which in operation moves downward and raises the hammer-rest when the soft pedal is operated, as will be understood by those skilled in the art. It will be seen that as the hammer-rest is adjusted to vary the position of the hammers for soft pedal, 85 soft touch, or soft blow the keys will be lifted at their rear ends, keeping the jacks in the proper position at the hammer-butts, preserving the elasticity of the touch, and avoiding the looseness of action of the key-levers, as 90 referred to hereinbefore.

Having thus described my invention, what I claim as new is—

1. In a piano, the combination of the key bottom or frame, the lifter arranged at the rear 95 edge of such bottom and movable, whereby it may be operated to lift the keys, the rocker D, arranged close below said bottom, pivoted between its ends and having an end engaging the lifter and its opposite end connected 100

with the soft pedal, and the rod connecting such soft pedal with the rocker D, substantially as set forth.

2. The combination, with the keys and the frame, of the lifter arranged under the rear ends of the keys, such lifter being hinged at the upper side of the frame and provided with a portion extended down to the lower side of the said frame, substantially as set forth.

3. The combination, with the keys and the frame below the same, of the lifter having a body portion rested upon and hinged to said frame and provided with a depending portion extended down alongside the rear edge of such frame, substantially as set forth.

JOSEPH CONRAD PRICE.
